UNITED STATES PATENT OFFICE

GERALD A. FITZGIBBONS, OF ST. LOUIS, MISSOURI

RACK

Application filed December 4, 1929. Serial No. 411,525.

The present invention relates to improvements in racks and relates more particularly to an improved rack for holding stocks of a number of different publications whereby the publications will be attractively displayed and held subject to the ready withdrawal of the same by purchasers.

It is an object of the invention to provide a rack of this character which is adapted to be set up in the vestibules of churches for holding large stocks of a variety of religious publications in which the booklets or publications are entirely visible and not partially covered.

15 A further object of the invention resides in providing an improved rack equipped with sliding dividers to hold booklets of any size and to retain the booklets in close proximity to one another to avoid unsightly gaps between the booklets whereby the entire rack display may contribute to a harmonious and neat appearance.

It is a further object of the invention to provide an improved rack including a top section for a changeable sign announcing new booklets.

30 A still further object of the invention is to provide an improved booklet rack of a light, portable and yet strong and rigid structure equipped with an easel support and with a hanging chain.

With the foregoing and other objects in view, the invention will be more fully described hereinafter, and will be more particularly pointed out in the claim appended hereto.

35 In the drawings, wherein like symbols refer to like or corresponding parts throughout the several views.

40 Figure 1 is a front elevation of an improved rack constructed according to the present invention.

45 Figure 2 is a rear elevation of the same with parts broken away and parts shown in section.

Figure 3 is a vertical central sectional view taken on the line 3—3 in Figure 1.

Figure 4 is a horizontal sectional view taken on the line 4—4 in Figure 3.

Figure 5 is a perspective view of the improved top section.

Figure 6 is a similar view of one of the end dividers, and

Figure 7 is also a perspective view showing a form of intermediate divider.

Referring more particularly to the drawings, 10 designates the lowermost section of the rack which is preferably made from thin light sheet metal. At its lower edge this lower section 10 is bent to form a shelf 11 and, outwardly of the shelf, to provide a flange 12 upstanding from the shelf 11 in order to retain the booklets or other publications upon such shelf. The upper edge of the section 10 is turned outwardly at right angles to form a retaining flange 13. It will be noted that the section 10 is of very short vertical dimension as compared with its horizontal width whereby to secure strength and rigidity throughout the entire base of the rack which is composed of a succession of sections similar to the section 10.

The next higher section 14 is formed with a ledge or shelf 15 having at its outer end an upstanding flange 16. The upper edge of the section 14 is shaped to provide a retaining flange 17. The retaining flange 18 of the lowermost section 10 abuts against the shelf 15 of the adjacent intermediate section 14 and the parts along this meeting line are jointed, as by electric welding or the like. The rack may thus be built up of contiguous sections of sheet metal having flanged shelves at the lower ends thereof and short retaining flanges at their upper ends welded or otherwise united to the shelves of adjacent sections.

The various sections may if desired be of different heights in order to accommodate publications of different sizes. The uppermost section 18 is also provided with a shelf

19 and with a shelf flange 20 at its lower edge, but unlike the other sections, this uppermost section 18 has its upper edge bent rearwardly to form a rear stiffening flange 21. This flange 21 is cut away as indicated at 22 and 23 in Figure 2 to provide for the passage of the legs 24 of the top or head section; which legs find support in the metal straps 25 welded or otherwise secured to the back of the uppermost section 18.

10 This top or head section is shown more particularly in Figure 5. The legs 24 thereof extend up and carry the channel guide strips 26 and 27, to the lower ends of which are secured the bottom trough 28, and to the upper ends of which are secured the lateral confining strips 29. These parts constitute a frame open in front and in back and in which a card or sign may be introduced by a sliding movement downwardly through the strips 29 and guides 26 and 27, the lower edge of such card or sign resting in the trough and the legend upon the sign being visible through the open rectangular portion of the framework. It is the purpose of this sign to convey messages to the public with respect to the issue of new publications.

15 In other words it constitutes an announcement bulletin of late works.

Now the base of the rack composed of the various sections above referred to is preferably braced and reinforced by metallic piping or hollow cylindrical members 30 and 31 which extend both transversely and longitudinally of the device and which are electrically welded or otherwise secured to such base sections. The vertical pipe members 31 project below the rack and act as feet for supporting the same. Such feet may be provided with rubber pads if desired. The ends of these members may be joined together also by welding or otherwise if desired. The upper ends of the vertical members 31 are adapted to receive the end links of a chain 32 which is useful for suspending the device from a wall or other support. The rack also preferably carries an easel support whereby it may be stood upon the floor or other supporting surface as indicated in Figure 3. This easel support includes the legs 33 braced by a cross bar 34 near the lower ends thereof and attached to the upper cross bar 35 which is pivotally mounted in the bearing strips 36 welded or otherwise secured to the back of the rack.

Intermediately of the lower and upper edges of each section is a guide strip for the sliding dividers.

The base of each guide strip is indicated at 37 and the flanges thereof at 38 and 39. The guide strips are also preferably of sheet metal and the flanges 38 and 39 thereof are bent upwardly and turn inwardly, such flanges being separated to provide a slot in the outer portions of the guide strips for slid-

ably receiving the dividers. The base members 37 of the guide strips are welded or otherwise secured to the sections. The end dividers are shown in Figure 6, comprising base flanges 40, upstanding webs 41 and heads 42 composed of the upper and lower members 42 and 43. These dividers are also preferably formed of sheet metal and the members 42 and 43 are folded one upon another along the edge 44. Notches 45 are cut in the webs 41 to receive the flanges 38 and 39 of the guide strips 37.

Referring more particularly to Figure 7, the intermediate dividers are formed with base flanges 46, upstanding webs 47 and heads 48 composed of the overlapped parts 48 and 49; the part 49 extending equally to both sides of the web 47 and adapted to encompass publications at opposite sides of such web 47. Notches 50 are provided in the webs 47 to receive the flanges 38 and 39 of the guide strips.

A coin box 51 is shown in Figures 2 and 3 as being affixed by bolts or other fastenings 52 to the rear side of the rack and in register with a coin chute 53 which extends through the rack and is accessible on the outside of the rack for the deposit of coins in payment for the publications and booklets. The shelf flange just above the coin chute 53 provides a support for the sign cards 54, such cards being clamped upon the flange as by a bolt 55. The outermost card may contain some such legend as "Coin box here".

In the use of the device, books or publications as indicated in dotted lines at 56 in Figures 1 and 4 are placed in the rack, in any suitable number, the lower edges of the stock of publications resting upon the ledge 11 and being confined by the outer flange 12. The side edges of such publications are embraced by the adjacent heads of intermediate dividers. These dividers in combination with the ledges and their flanges constitute open pockets to receive the publications while leaving the upper ends of the publications free to be withdrawn upwardly by the purchaser. The dividers are slidable laterally in the guide strips and they are thus enabled to engage the publications without regard to the sizes of the same.

The device is set up either upon the easel support or is hung from the chain 32. All of the publications are exposed to view and none of them are overlapped or obscured by one another. Thus they are attractively displayed to the eye of the purchaser who may readily withdraw the publication of his choice after which he deposits a coin in the coin chute 53 in payment of same. The coin box 51 may be removed from time to time by withdrawing the bolts 52.

It is obvious that various changes and modifications may be made in the details of construction and design of the above spe-

cifically described embodiment of this invention without departing from the spirit thereof, such changes and modifications being restricted only by the scope of the following 5 claim:

What is claimed is:—

A display rack comprising a succession of sheet metal base sections disposed in edge-wise abutting and superposed relation, each 10 base section having at its lower edge an out-turned shelf portion and at its upper edge an outturned retaining flange abutting the lower side of the shelf portion of the adjacent base section, and reinforcing and supporting 15 members secured to and extending across the rear sides of said base sections to hold the same together and in upright position.

In testimony whereof I affix my signature.

GERALD A. FITZGIBBONS.
